UNITED STATES PATENT OFFICE.

ARTHUR J. HELMS, OF PORTLAND, OREGON, ASSIGNOR, BY DIRECT AND MESNE ASSIGNMENTS, TO INVENTORS DEVELOPMENT COMPANY, OF PORTLAND, OREGON.

MITER-BOX.

1,290,188.

Specification of Letters Patent.

Patented Jan. 7, 1919.

Application filed August 3, 1916. Serial No. 112,980.

To all whom it may concern:

Be it known that I, ARTHUR J. HELMS, a citizen of the United States, residing in the city of Portland, county of Multnomah, 5 and State of Oregon, have invented certain new and useful Improvements in Miter-Boxes, of which the following is a specification.

My invention relates to miter boxes and 10 has among its salient objects: to provide in combination with a body, a pair of adjustable saw guides for holding a saw in a vertical plane for operation horizontally, or for operation in an inclined position, be- 15 tween the horizontal and the vertical, which saw guides are adjustable bodily toward and from each other at opposite sides of the piece being sawed, whereby to assist in holding the piece being sawed during the 20 sawing operation; to provide in combination with the body of said device an adjustable support for the piece to be sawed, which support is pivoted to turn upon a vertical axis, whereby to hold the piece to be sawed 25 at any adjustable angle in a horizontal plane; to provide a two-part adjustable support, one part of which is adjustable relative to the other part about its longitudinal axis to different angles, whereby to make possi- 30 ble the cutting of a piece of wood on a compound angle; to provide a device which can be collapsed and folded together, whereby to occupy a small compass when not in use; and, in general, to provide a simple and 35 practical miter box of the character referred to.

In order that others may understand my invention, I have illustrated one practical embodiment thereof in the accompanying 40 sheet of drawings, which I will now describe.

Figure 1 is a top plan view thereof;

Fig. 2 is a side elevation of the device with a part shown in section on line 2—2 of 45 Fig. 1;

Fig. 3 is an end view looking at the right hand end of Fig. 1, with the saw indicated in light dotted lines; and

Fig. 4 is an end view, looking at the left- 50 hand end of Fig. 2.

Referring now more in detail to the drawings, my invention comprises a body 1, preferably composed of two spaced members 1^a and 1^b, with spacing pieces 2—2, at their 55 opposite ends. Slidably mounted between

said parts 1^a and 1^b, at opposite ends, are two pairs of guide members 3—3, with a connecting bolt 4, for each pair, provided with a thumb-nut 5, for tightening said guide members 3—3, in whatever positions 60 toward and from each other they may be adjusted. Secured to the outer ends of said bolts 4—4, are guide pieces 6—6, the heads of the bolts 4, being countersunk in the outer sides of said guide pieces 6—6, as clearly 65 indicated in dotted lines, said guide pieces being adapted to turn upon said bolt, whereby to be adjusted to any positions around said bolts.

Slidably mounted upon each of said guide pieces 6—6, is a saw guide 7, having a projecting guide 8, attached at its upper end and spaced from the body of said guide 7, to form a slideway 9, open at its lower end, for the saw. As the guide pieces 6—6, can 70 be turned upon the bolts 4—4, it will be evident that the saw can be operated by a straight horizontal movement, or that it can be operated on an incline, with the point of the saw directed downwardly, as indicated in Fig. 3.

Pivottally mounted upon the body 1, is a support 10, said support being provided at its attached end with a round portion 11, set into a corresponding socket 12, formed 85 in the upper side of the body 1, as clearly shown in Fig. 2. The attached end of said support is rounded, as at 10^a, and a scale 10^b, is provided to determine its position of adjustment relative to the body 1. 90

In order to lock said supporting member 10, in adjusted positions, it is provided in its rounded edge with a groove 13, in which fits a nut 14, attached to a thumb screw 15, which can be set so as to lock said support 95 in adjusted positions. Hinged to one side of said support 10, is an adjustable part 16, which can be let down into the same plane with the part 10, or can be adjusted to an angle relative to the same, as shown in Fig. 100 4, said part 16, being provided with a holding bar 17, provided with a thumb screw 18, adapted to move in a curved slot 19, in a segment 20, provided with graduations, as at 21. The end of the bar 17, is pointed, as at 22, to indicate the angle. The adjustable member 16, is beveled at its inner end so as to give clearance when said support 10, is turned upon its pivotal attachment to the body 1, toward the top in Fig. 2. Thus 110

it will be seen that a molding, or other piece of wood, can be sawed square off on any angle by resting it flat-wise upon the support 10, and projecting it into the path of the saw, or it can be sawed on a compound angle by being held up against the part 16, which can be adjusted relative to the body 1, with the piece to be sawed projecting into the path of the saw.

- 10 A pivoted extension piece 23, may be attached, as at 24, to the beveled end of the member 16, as shown, to be moved out at will to form a continuation of said member 16, at its beveled end, when needed, said 15 piece 23, being of the same thickness as said member 16, and having a thin segmental portion 25, which telescopes into the end of said member 16, as indicated in dotted lines, said thin portion being provided with a 20 curved slot 26, through which a stop pin 27 projects.

I am aware that changes can be made in my invention as here illustrated without departing from the spirit thereof, and I do 25 not, therefore, limit said invention to the particular showing here made, except as I may be limited by the hereto appended claims.

I claim:

- 30 1. A miter device of the character referred to comprising in combination a body, two vertical saw guides adjustable toward and from each other longitudinally along said body, a supporting member pivotally connected at its end to said body between its ends and adapted to be adjusted to different angles in a horizontal plane relative to said body, said supporting member also having a portion adjustable about an axis extending longitudinally thereof, whereby to turn the piece to be sawed about an axis extending longitudinally thereof.

- 45 2. A miter box of the character referred to comprising in combination a body, two vertically disposed guide pieces adjustably and pivotally connected to said body and adjustable both pivotally and bodily toward and from each other longitudinally along said body, saw guides slidably connected 50 with said guide pieces and adapted to receive a saw blade, a supporting member adjustably attached at its end to said body between its ends and adapted to hold the piece to be sawed at different angles in a horizontal plane, cross-wise of said body and in the path of said saw, substantially as described.

- 55 3. A miter box of the character referred

to comprising in combination a body, two vertically disposed guide pieces adjustable toward and from each other in the same plane longitudinally of said body, saw guides slidably connected with said guide pieces and adapted to receive a saw blade, a two-part supporting member pivotally attached at one end to said body, one part of said supporting member being beveled at one end and hingedly attached to the other part thereof, whereby to be moved about its longitudinal axis to different angles relative thereto, substantially as and for the purpose described.

4. A miter box of the character referred to comprising in combination a body, vertical guide pieces pivotally and adjustably attached to said body and adapted to be adjusted toward and from each other along said body in the same plane, saw guides slidably mounted upon said guide pieces, a supporting member pivotally attached to said body between said guide pieces and projecting laterally therefrom, said supporting member having a part adjustable around a longitudinal axis, with means for holding the same, and means for securing said supporting member in adjusted positions on its pivotal connection to said body, substantially as shown and described.

5. A miter box of the character referred to comprising in combination a body member, guide members slidably secured to said body member and adjustable longitudinally thereof toward and from each other, with means for securing the same in adjusted positions, guide pieces pivotally connected to said guide members at one side of said body and movable therewith, saw guides slidably connected with said guide pieces and adapted to receive a saw blade extended from one to the other, a supporting member pivotally and detachably connected at one end to said body intermediate its ends, and adjustable to different angles relative to said body, said supporting member having a part hingedly connected along one side thereof with means for adjusting and holding the same in different angles relative thereto, said adjustable part being beveled at one end and provided with an adjustable extension, substantially as shown and described.

Signed at Portland, Multnomah county, Oregon, this 27th day of July, 1916.

ARTHUR J. HELMS.

In presence of—

J. C. SIMMONS,
J. C. STRENG.
